HOOK-AX

Buford Dobbs, Box 229, Fayette, Ala.

Filed Nov. 23, 1964, Ser. No. 82,750

Term of patent 14 years

(Cl. D93—4)

FIG. 1 is a side elevational view showing one side of my hook-ax, the other side being identical to the side shown;

FIG. 2 is an end view showing the hook portion of the hook-ax, the handle being broken away;

FIG. 3 is a top plan view of the hook-ax; and

FIG. 4 is a sectional view taken along the line 4—4 of FIG. 1.

I claim:

The ornamental design for a hook-ax, as shown and described.
